[57] CLAIM

The ornamental design for a hacksaw blade holder, substantially as shown.

DESCRIPTION

FIG. 1 is a view in side elevation of a hacksaw blade holder, showing my new design,
FIG. 2 is a view taken from the opposite side thereof,
FIG. 3 is a top plan view thereof,
FIG. 4 is a bottom plan view thereof,
FIG. 5 is a front view thereof,
FIG. 6 is a rear view thereof; and
FIG. 7 is a sectional view taken on line 7—7 in FIG. 2.

FIG. 1

FIG. 2

FIG. 3

FIG. 4

FIG. 7

FIG. 5

FIG. 6
